UNITED STATES PATENT OFFICE

JAMES J. FITL, OF SWANTON, NEBRASKA

GRAVE VASE

Application filed August 30, 1929. Serial No. 389,402.

This invention relates to cut flower holders and has relation more particularly to a device of this kind especially adapted and designed for use in connection with the decoration of graves, lawns and cemeteries in general.

It is an object of the invention to provide a device of this kind which will not tip over or become blown over when placed in a position exposed to the wind.

A further object of the invention is to provide a reversible device which may not only be attached to the soil or sod upon a convex grave mound but may also be placed in an operative position upon a flat indurate object such as a tombstone.

A still further object of the invention is to provide a construction which can be economically manufactured and sold at a reasonable retail price within the means of the general purchasing public.

Another object of the invention is to provide a device which is of practically no utility for other purposes than as is herein mentioned.

Other and further objects and advantages of the invention will be understood from the following detailed description and it is thought to be obvious that a grave vase constructed in accordance with my invention is particularly well adapted for use by reason of the convenience and facility with which it may be assembled and operated, and it will also be obvious that my invention is susceptible of some change and modification as to its minor details and arrangement of parts without departing from the principles and spirit thereof and for this reason I do not wish it to be understood as limiting myself to the precise arrangement and formation of the several parts herein shown in carrying out my invention in practice except as herein-after claimed.

In order that my invention may be better understood, I now proceed to describe the same with reference to the accompanying drawing wherein:

Figure 1 is a perspective view of the device, the detachable base thereof being in a reversed position as applied to a hard indur-

rate object such as a tombstone, the latter being decorated by a memorial wreath supported by the device.

Figure 2 is a view partly in section and partly in elevation illustrating the device as applied to a convex grave mound, and

Figure 3 is an enlarged detail showing a fragment of the base member and a modification of the vase supporting means.

Referring now to the drawings for a more particular description the numeral 10 indicates a vase adapted to hold flowers. The vase is preferably formed of sheet metal and is of conical-shape preferably in order that the vessel will not be practical for any purpose other than the herein described utility. The apex of the cone is provided with a shaft or pintle end 11 which is preferably formed of galvanized iron in order that soldering may be facilitated and it will be understood that the member 11 is secured to the vase 10 by any suitable means such as the soldering shown at 12 which also provides a watertight joint at said apex. A threaded galvanized bolt may be used in lieu of the shaft 11. The vase 10 may be formed of cast iron if desired and the shaft 11 cast integral therewith and in case threads are desired upon the shaft 11 the same may comprise a threaded bolt the head of which is placed within the mass at the apex of the cone during the casting of the latter.

The base 13 is preferably formed of concrete but may be made of cast iron. If formed of concrete the reinforcing wires 14 are preferably employed, the latter being secured from chicken or fence wire of small mesh cut to a suitable size and configuration.

The base 13 is preferably circular in shape and may be of a suitable thickness in order to provide a comparatively great weight for purposes later described. A bushing 15 is preferably placed in the center of the disc 13 when concrete is employed and the bushing 15 is preferably formed of iron and if desired the sleeve or bushing 15 may be provided with interior screw threads as shown in Figure 3 and in such case the member 11 is similarly provided with screw threads for purposes later described. When the disc is

formed of cast iron the bushing 15 may be dispensed with.

A plurality of spikes such as 16-penny nails and indicated at 16 are formed integral with the base during the casting thereof and in a manner whereby their sharpened pointed ends are exposed as shown in Figure 2. The entire device is dipped in green paint prior to distribution for use.

10 In the operation of the device, in case it is desired to decorate a grave mound which is usually of convex contour such as indicated at 17 in Figure 2, the disc 13 is first attached to the soil or sod by means of pushing the 15 spikes 16 downwardly therein and at this time the operator may stand or jump upon the disc for forcing the spikes into the soil or loose uneven soft sod and thus provide a rigid support for the vase. The vase 10 is 20 now filled with cut flowers such as indicated at 18 in Figure 1 and the pintle end of the vase or its shaft 11 is inserted or screwed into the base 13.

At times when it is desired to place the 25 ornament and flowers upon an indurate flat surface such as the tombstone 19 shown in Figure 1, the base 13 is placed upon the surface thereof with its spikes 16 in an upward position and the vase is attached to the base 30 member as heretofore described and since the base 13 is of comparatively great weight the device will remain in an upright position at all times and during windy weather. At this time the upright spikes 16 function as a support from which a wreath 21 shown in Figure 1 may be suspended for a memorial 35 decoration of the tombstone.

As indicated by the numeral 20 each vase 10 may be provided with individual serial 40 numbers if desired and the base member 13 may be similarly provided with corresponding numbers for the purpose of easily identifying the owner thereof should the vase become mislaid by the cemetery employees during winter storage of a large number of 45 devices, a book containing the owner's name and said numbers being kept for such purpose.

It is obvious that the base member is of 50 small practical utility for any purpose except as herein described. Similarly, the vase being conical in shape will not function as a vessel for holding water without the base in that it will not support itself in an upright position and, therefore, is of practically no 55 utility other than as a grave vase and for this reason the removal thereof by unauthorized persons is highly minimized.

I claim:—

1. A grave vase comprising a weighted 60 disc, pins projecting from the disc, a threaded bushing extending through the disc and spaced inwardly of the pins, a cup, and a threaded pintle carried by the cup for engaging in the bushing.
- 65 2. A grave vase comprising a flat weighted

base, a bushing extending therethrough, a cup, a pintle on the cup for fitting in the bushing, and pins on the base spaced away from the bushing and pintle.

3. A grave vase comprising a weighted 70 base, a bushing in the base opening through both sides of the vase, a cup, and a pintle carried by the cup for removably fitting the bushing.

4. A grave vase comprising a flat weighted 75 reversible base having an opening therein accessible from both faces of the base, a cup having means to removably fit the opening from either face of the base, and pins on the base spaced about the opening and away from 80 the cup.

In testimony whereof, I have affixed my signature.

JAMES J. FITL.
